STORAGE BATTERY PLATE ASSEMBLY

Charles D. Galloway, Wyndmoor, Pa., assignor to
The Electric Storage Battery Company, a cor-
poration of New Jersey

Original application June 3, 1944, Serial No.
538,564. Divided and this application Decem-
ber 19, 1944, Serial No. 568,797

2 Claims. (Cl. 136—134)

1

This invention relates to the manufacture of elements for storage batteries, and more especially to the production of an assembly group of positive or negative plates, united in parallel relation to a common connecting strap, to produce a novel and improved structure.

It has been customary to unite the plates of such a group to the strap by means of lugs projecting from the upper margins of the plates which lugs are united to the connecting strap either by inserting them into slots in the strap and puddling molten metal by a lead burning operation in the spaces between the lugs and the strap or by first assembling the group of plates and there casting the strap around the projecting lugs in a suitable mold. In either case, in order to produce an autogenous weld between the lugs and the strap, it has been necessary either to fuse the lugs and surrounding metal of the strap as in the puddling method, or by pouring molten metal into the mold at a sufficiently high temperature to melt the lugs, in the casting method. In either case it is practically impossible to control the temperature of the molten metal to avoid softening or partially fusing the metal of the lugs below the under surface of the strap, resulting in recrystallization of the metal at these points, thus weakening the lugs where the greatest stresses must be met due to vibration during assembly and in service.

It is an object of this invention to provide a group assembly of plates and strap in which this defect is eliminated.

It is a further object of this invention to provide a group assembly in which the plate lugs are autogenously welded to the metal of the strap only along and near their upper edges but below are in intimate mechanical contact with the strap metal without fusion therewith.

It is a further object of the invention to provide a group assembly in which the plate lugs are autogenously welded to the metal of the strap only along and near their upper edges while below they are gripped between the confronting surfaces of the strap by shrinkage pressure without fusion.

This application is a division of my copending application Serial No. 538,564, filed June 3, 1944, and is directed to the product of the process and apparatus described in that application.

The invention will be more clearly understood by referring to one embodiment thereof described below in connection with the accompanying drawing in which:

Fig. 1 is a plan view of a mold for casting straps

2

on terminal lugs to form an assembly embodying features of the invention;

Fig. 2 is a sectional elevation on the line 2—2 of Fig. 1 showing also a portion of the inverted element; and

Figure 3 is a detailed section of the strap and lug portion of a storage battery element embodying features of this invention.

In the drawing, 10 represents the mold block of any suitable material such as cast iron. It is provided with open top shallow mold cavities 11 and 12 of suitable shape and dimensions for casting the desired connecting straps. As shown in Fig. 2, the assembled element comprising positive plates 13, negative plates 14 and interposed separators 15, is located in an inverted position with the plate lugs 16 and 17 projecting downwardly into the corresponding mold cavities 11 and 12. The element may be held together by any suitable clamping device (not shown). The element is supported vertically on a slab 18 of heat-insulating and heat-resisting material such as that known to the trade as "Transite" whose upper surface is slightly above the upper surface of the mold proper. As shown in Fig. 2, the edges of the separators 15 rest on this slab and are thus prevented from coming into contact with the heated mold.

The mold cavities are provided with downwardly extending conical cavities 19 and 20 for integrally casting the terminal posts on the straps. Ejector pins 21 and 22 are shown at the base of the post cavities 19 and 20 for removing the completed element with attached strap-castings from the mold. The ejector pins may be actuated by any suitable means not shown.

To provide for filling the mold, the gate cavities 23 and 24, located in gate blocks 25 and 26, are shown, through which the molten metal may be poured into the mold cavities proper. The gate blocks are here shown as detachable but may be integral with the mold block. After the castings have solidified, the gates may be cut off either after the element and strap-castings have been removed from the mold or before removal. In the latter case, the gate blocks 25 and 26 will first be removed and the gates cut off in situ by any suitable means not shown.

Inserted through and closely fitting into suitable openings in the floor of the mold cavities 11 and 12 are the super-heating inserts 27 and 28, respectively. Since these inserts are alike, the one shown at 27 will now be described. It comprises a block of steel or similar heat-conducting refractory metal whose upper rectangular face

is flush with the floor of the mold cavity 11 and is longitudinally substantially coextensive with that cavity. In width, it corresponds with the horizontal length of the plate lugs 16 and is located immediately below the row of these positive plate lugs. The vertical dimensions of the plate lugs 16 as here shown are such as to bring their ends close to but not actually in contact with the insert 27, leaving a narrow space 29 therebetween. Under some conditions, however, it may be satisfactory to bring these plate lugs into actual contact with the insert. Except for a short distance from its upper surface, the insert 27 is out of contact with the mold, there being interposed a clearance space 30 to limit the transfer of heat from the insert to the mold. The insert 27 is provided with a downwardly extending projection 31 which is surrounded by a tubular water-cooled electrical conducting coil 32 adapted to carry high-frequency alternating current for inductively heating the insert 27 in the well-known manner. Standard apparatus for developing and applying suitable high-frequency current for inductive heating is available on the market and it is not deemed necessary to illustrate or describe it here.

The insert 27 is provided with a duct 33 through which cooling-liquid may be circulated and suitably controlled as by the valve 34.

The operation of the apparatus above described is as follows:

The assembled element, comprising the desired number of positive and negative plates with interposed separators clamped together in their final relative positions, is inverted and supported on the mold as shown in Fig. 2, with the separators resting on the slab 18 and the plate lugs extending into the mold cavities 11 and 12, with their ends above and close to or in contact with the upper surfaces of the inserts 27 and 28, respectively. Molten metal, preferably lead-antimony alloy, is then poured into the mold cavities 11 and 12 via the gates 23 and 24 until the cavities are filled to the upper level including the spaces between and beneath the plate lugs. The temperature of the molten metal is such that the plate lugs will not be melted or softened but will retain their shape or physical identity, as it has been found that such melting or softening produces recrystallization or grain growth and weakening of the lugs, causing them to break when subjected to stress or vibration in service. The shrinkage of the molten metal on cooling and solidifying, which occurs as the molten metal contacts the cooler surfaces of the lugs and mold, firmly grips the plate lugs and holds them mechanically attached to the straps. However, such mechanical contact between the lugs and the strap does not provide maximum and uniform electrical conductivity to insure minimum voltage drop and equal distribution of current between the plates when discharging at high rates. Accordingly, the under surface of the strap-casting, formed by the molten metal now around the plate lugs, as it rests in the mold, together with the tips of the plate lugs are in a brief period of time raised to an elevated temperature to effect a welding or fusing of the lugs to the strap for only a short distance above the floor of the mold and without melting or fusing the roots or major portion of the lugs. The heat necessary for the localized welding or fusing of the lugs is applied through the super-heating inserts 27 and 28. In the illustrated form of the invention the shanks

of the inserts are surrounded by high-frequency heating coils 32. High-frequency current is passed through the heating coils 32 to heat inductively the inserts 27 and 28, the intensity and duration of the current being such as to melt the metal just above the upper surfaces of the inserts and melt the tips of the plate lugs, thus welding them together for only a short distance, without melting or softening the roots or major portion of the lugs gripped mechanically in the strap-casting. The intensity and duration of the current required to obtain the best results will vary with the dimensions of the strap-casting and the size and spacing of the plate lugs. With the volume of current available from standard apparatus for inductive heating applied to a standard type of storage battery element, a few seconds has been found adequate to give satisfactory results. As soon as the current is interrupted, cooling-water is circulated through the ducts in the inserts to prevent further heating effect and also to hasten the cooling, solidification and final shrinkage of the strap around the lug roots.

The length of the mold cavities 11 and 12 may be made sufficient to provide for the maximum width of element. For smaller elements, it is only necessary to block off the ends of the mold cavities. No other adjustment is necessary to provide for elements of various numbers or thicknesses of plates or various plate spacing.

It may be remarked that space is provided above the level of the molten metal in the mold and at the roots of the lugs for the access of air, which tends to keep the metal cool at the roots of the lugs and also to keep the adjacent portions of the separators cool.

It will be noted that there is provided, in accordance with this invention, a group of storage battery plates assembled by their conducting lugs to a suitable connecting strap, wherein the plate lugs at their roots and over the major portion of their length adjacent the plates are mechanically tightly gripped by the adjacent metal of the strap without being autogenously welded thereto, while the tips of the lugs are autogenously welded to the adjacent metal of the strap, as shown in Fig. 3.

While one convenient form of apparatus for carrying out the process and producing the product of this invention has been described, including inductively heated means for applying the superheating temperature locally to the tips of the plate lugs and the adjacent metal of the strap casting, it is not intended to limit the scope of the invention to this particular apparatus since other means may be employed for applying localized superheating for the selective and localized fusing of the end portions of the lugs to the adjacent metal of the strap.

The described mold for the manufacture of storage batteries is not claimed since it is the subject matter of my original application Serial No. 538,564, nor is the described process claimed herein because it is the subject matter of my divisional application Serial No. 569,387, filed December 22, 1944, and assigned to the assignee of this application.

It will be obvious to those skilled in the art that modifications may be made in details of construction and procedure without departing from the spirit of the invention which is not limited in respect to such matters or otherwise than the appended claims may require.

I claim:

1. A storage battery element comprising alternately disposed positive and negative plates with interposed separators, said plates provided with terminal lugs assembled respectively to positive and negative straps wherein the roots of the lugs are tightly shrinkage gripped by but separate from the adjacent metal of the strap and the tips of the lugs are autogenously welded to said metal.
  2. For a storage battery cell, a group of plates provided with terminal lugs assembled to a connecting strap wherein the lugs over a major portion of their length adjacent the plates are tightly shrinkage gripped by but are separate from the adjacent metal of the strap and the tips of the lugs are autogenously welded to said metal.
